US0D1051378S

(12) **United States Design Patent** (10) **Patent No.:** **US D1,051,378 S**
(45) **Date of Patent:** **** Nov. 12, 2024**

(54) **SYRINGE PISTON**

(71) Applicant: **Estar Technologies Ltd**, Holon (IL)

(72) Inventor: **Aaron Esteron**, Holon (IL)

(73) Assignee: **ESTAR TECHNOLOGIES LTD.**,
Holon (IL)

(**) Term: **15 Years**

(21) Appl. No.: **35/517,864**

(22) Filed: **Jul. 3, 2023**

(80) **Hague Agreement Data**

Int. Filing Date: **Jul. 3, 2023**

Int. Reg. No.: **DM/230225**

Int. Reg. Date: **Jul. 3, 2023**

Int. Reg. Pub. Date: **Jul. 21, 2023**

(30) **Foreign Application Priority Data**
